REACTIVE STOKER

Frank C. Greene, Milwaukee, Wis.

Application January 14, 1928. Serial No. 246,686

12 Claims. (Cl. 110—101)

The present invention relates to a stoker intended for use in connection with domestic heating units, and the object of the invention is to provide such a stoker which shall be automatic 5 in its operation, which shall require a minimum of attention, and which shall be simple in construction and extremely efficient in operation. To the accomplishment of the foregoing and related ends, said invention, then, consists of the means 10 hereinafter fully described and particularly pointed out in the claims.

The annexed drawings and the following description set forth in detail certain mechanism embodying the invention, such disclosed means 15 constituting, however, but one of various mechanical forms in which the principle of the invention may be used.

In said annexed drawings:

Fig. 1 is a vertical section through a stoker contemplated by the present invention showing a furnace in dotted outline; and Fig. 2 is an enlarged horizontal section through the base of the stoker taken along the line 2—2 of Fig. 1.

The reference numeral 1 indicates a basin 25 adapted to be mounted beneath the combustion chamber of the furnace and provided with an upstanding screw-threaded projection 2. The threads of the projection 2 are of the left-hand type to insure against loosening of the stator 3 30 during operation of the stoker. The stator 3 is screw threaded to the projection 2 and is provided with a thread 4 extending throughout its length. It will be noted that the lower portion 4^a of the thread is much heavier than the upper portion 35 4^b of the thread, and that the thickness of the thread decreases progressively from the bottom to the top of the stator. Obviously this variation in the thickness of the thread causes also a variation in the distance between the adjacent 40 volutions of the thread at the lower and at the upper portion of the stator. Thus, the distance 4' is less than the distance 4''. One reason for this variation lies in the fact that, as the fuel is heated, the evolved free moisture causes differing friction and the mass moves slower, hence it is 45 necessary to provide increased space to accommodate such slower moving mass. Furthermore, the increase in the distance between adjacent turns of thread 4 slightly releases the friction 50 between the ribbon of fuel and the screw, thus increasing the efficiency of the screw. It will be readily understood that certain fuels will expand as they are heated, and this variation also compensates for such expansion. The stator is formed 55 with a longitudinal bore 5 registering with a simi-

lar bore in the basin 1 and with outlet ports registering with a similar bore in the basin 1 and with outlet ports 6 at its upper end providing for communication between the bore 5 and the interior 60 of the furnace.

Through the agency of bolts 7, or similar fastening means, the downturned flange 8 of the grate 9 having air inlet apertures 10 therein is attached to a tubular rotor 40 hereinafter to be described. A shield 11, comprising a cylindrical portion surrounding the muffle and spaced therefrom and a conical portion 12, the edge of which is received in a rabbeted recess 13 in the grate 9, insulates to a considerable and necessary extent, the tubular rotor and stator from the heat generated in 70 the combustion chamber of the furnace. A cowl 14 is attached to the shield 11 and overhangs the shield as indicated at 15. The shield is provided with a plurality of apertures 16 at its upper end to permit the passage of air from the space 11' 75 between the shield and the tubular rotor into the combustion chamber of the furnace. If it should appear desirable, the shield space 11' may be partially or entirely filled with insulating material 80 or other heat shielding means to reduce the temperature of the coal within the tubular rotor 40. It will be readily understood that certain fuels become activated at a lower temperature than do others, and if the fuel is raised beyond its critical temperature before it is discharged into the combustion chamber, the advantages of the activation are reduced. As is clearly illustrated, the cowl 14 is frusto-conical in form, and the upper 85 end of the tubular rotor is beveled as at 17 to form a continuation of the outer surface of the 90 cowl 14.

The basin 1 is provided at one side with an inlet conduit 18 inclined upwardly as shown. A hopper 19 is mounted adjacent the furnace and is formed with inclined walls 20 tapering toward 95 its mouth 21. A hinge member 22 is carried by the hopper 19 at its upper outer edge, and said hinge member cooperates with a container 23. The container 23 has its one end open, and the walls of said container are thickened adjacent 100 said open end to form a beveled portion 24, which portion forms a seat for a slidable cover 25. The container 23 may assume either of the positions shown in the figure. In the dotted line position it may be filled with fuel, and in the full line position it is discharging into the hopper 19.

One wall 20 of the hopper forms a portion of a casing 26, in which is mounted a worm gear 27 carried by a tube 28, hereinafter to be described, and cooperating with a worm 29 on the spindle 110

of a motor 30 which is mounted beneath the hopper 19. The hopper, the casing 26, the motor 30, and an ash container 31, having a handle 32, may all be enclosed in a rectangular housing in order that the organization may present a neat and finished appearance.

A conduit 33 is rigidly attached to the casing 26 and, because of the inclination of the casing 26, is so inclined as to extend toward the conduit 18. The conduit 33 is formed with an aperture 34 in its upper surface adapted to receive ashes from the rotating grate 9, and an ash ejector 35 comprising a handle portion 36 and a hook portion 37 is provided for dragging the ashes from the

grate into said aperture. It will be readily understood that the handle portion 36 of the member 35 is positioned adjacent the conduit 33 and outside the furnace, while the hook portion 37 lies within the furnace.

The tube 28 is rotatably mounted within the conduit 33 and is journaled at one end in the casing 26 and at the other end in the inlet conduit 18 of the basin 1. The upper end 38 of the tube is sharply beveled and preferably toothed and is positioned adjacent the mouth 21 of the hopper 19. The lower end 39 of the tube is also beveled and is positioned adjacent the inner end of the inlet conduit 18. A gear 41 carried on the tube 28 bears against the outer end of the inlet conduit 18 and engages gear teeth 50 formed on the rotatable grate 9. The tube 28 is formed on its outer surface with a helical gapped thread 42 which contacts the inner surface of the conduit 33, and said conduit 33 is provided with an aperture 43 in the lower wall of its upper end overlying the ash container 31.

The tubular rotor 40 is a tubular element rotatably mounted to surround the stator 3 and has its lower end 44 enclosed within the basin 1. The tubular rotor is provided in its lower end with a lateral aperture 45 providing communication between the basin 1 and the space defined between the stator 3 and the tubular rotor 40, and carries a suitably shaped fin 46 adjacent said aperture.

The operation of the device is as follows. The container 23, having been filled with fuel, is rotated upon the hinge member 22 to the position indicated in full lines in the drawings. The hopper 19 is thus filled with fuel. When the motor 30 is started, it rotates the tube 28 through the medium of the worm 29 and the worm gear 27, and the beveled end 38 of the tube 28 tends to agitate the fuel in the lower end of the hopper 19, to break up any lumps fed thereto, and to eject to the sides material which cannot be broken up. This action prevents clogging of the mouth 21 of the hopper 19 and causes the fuel to fall into the open end of the tube 28. Due to the inclination of the tube 28, the rotation thereof will cause the fuel to gravitate therethrough and to be discharged from the lower end 39 of the tube into the conduit 18. The rotating beveled end 39 pushes the fuel thus discharged into the basin 1. The gear 41, rotating with the tube 28 and meshing with the gear teeth 50, rotates the grate 9, and, due to the connection 7 between the grate 9 and the tubular rotor 40, said tubular rotor is likewise rotated. The fin 46, rotating within the confines of the basin 1, directs the fuel into the interior of the tubular rotor 40. The inner walls of the muffle 40 may be roughened to provide for intimate frictional contact between said walls and the fuel contained in said tubular rotor and consequently the fuel is caused to rotate with the tubular rotor about the

stator 3. Such rotation obviously will cause the fuel to travel upwardly along the threads 4 of the stator and to be discharged from the top of the tubular rotor onto the cowl 14. Said cowl 14 prevents the entrance of coal into the shield space 11' and directs it into the combustion chamber of the furnace where it falls onto the hearth portion 12 of the shield 11. Due to the draft in the furnace, air is continually being drawn through the apertures 10 of the grate 9, the shield space 11' and the apertures 16 in the upper end of the shield 11. The overhang 15 of the cowl 14 directs the air downwardly onto the bed of fuel. This stream of air obviously will act as an insulator between the combustion chamber of the furnace and the tubular rotor 40, and will consequently prevent too rapid heating of the fuel mass contained within the tubular rotor, and further, this stream of air becomes highly heated and thus promotes immediate combustion of the vapors which are discharged from the upper end of the tubular rotor. It is to be understood that any vapors generated by the preheating of the coal in the tubular rotor are discharged from the upper end of the tubular rotor together with the coal. Air also enters the combustion chamber through the bore 5, discharging through the apertures 6 and thus coming into intimate contact with the said vapors to aid in the combustion thereof, and around the edge 9' of the grate 9 to enter the fire bed from the bottom.

The present invention has been described as a reactive stoker, and its primary object is to supply fuel (and more especially slack coal) to a furnace, such fuel having been endowed with a high index reactivity. Reactivity may be described as being a quality pertaining to solid fuels causing them to react with oxygen in a lively manner upon attaining their ignition temperature. It has been determined that the reactivity of a fuel is inversely proportional to its kindling temperature. It is furthermore known that coals subjected to preheating sufficient to distil off their tar vapors but not sufficiently preheated to crack such vapors to fixed gases have a high index of reactivity. Thus, coal distilled at low temperatures (500° C.) will exhibit high reactivity (index 72.5 in air), whereas coal distilled at high temperatures (1000° C.) will exhibit low reactivity (index 61.0 in air). The degree of reactivity appears to be affected by the time element as well. Thus, heating a suitable coal at a very low temperature for a great length of time may result in a fuel having an index of reactivity similar to that exhibited by the same coal when it has been heated at a somewhat higher temperature over a shorter period of time. Experiments have shown that unless the tubular rotor of a stoker of the present type is shielded from the temperatures prevailing in the combustion chambers of the furnace, the coal in the tubular rotor is preheated to too high a temperature for satisfactory results. Since the lighter distillate from a bituminous coal may evolve at about 200° C. and the melting point of the coal may average 300° C. with its last condensate coming off at 400° C. and with the tar vapors cracking to fixed gases at temperatures between 600° C. and 800° C., it will be seen that the most desirable temperature of the coal upon delivery to the combustion chamber will be somewhere near 450° C. Since the temperature of the combustion chamber may be 1000° C., or even higher, it is seen

that it is necessary to shield the coal within the tubular rotor from such high temperature or to pass the coal very rapidly into the furnace. The latter method appears to be impractical, and 5 the present invention contemplates the use of the former method.

To render coal active presumes a prior melting or at least incipient coke formation. It is not desirable to melt the coal below the top of the 10 tubular rotor, for, if the coal is so melted, then the mass is in a partially fluid state, somewhat like a grease for purposes of propulsion, and does not move upwardly on the stator as fast as the unmelted coal below it does. The result, in such 15 event, is that the faster moving unmelted coal invades the melted coal and makes a very dense and tough mass which is anything but the desired fuel. Such desired fuel is of very light weight (about four or five pounds per cubic foot). It is 20 very much more porous than any coke that is known to me. In this state it is highly reactive, ignites almost instantaneously, and, when discharged into the fire pot of a furnace, burns intensely with a draft and without smoke or resulting 25 clinker.

I am unable to state exactly what the reactions within the tubular rotor may be, but apparently the coal is preheated therein to a degree slightly below its melting point. This temperature of 30 melting may be said to range between 300° C. and 400° C. for a large number of coals. The pre-heated air coming from inside the stator 3 through the vents 6 combines with the gas or vapors which seem to be generated immediately the 35 mass exits from the top of the tubular rotor, at an ignition temperature possibly initiated by radiation by the burning fuel in the fire pot, or by radiation from the metal parts of the furnace or stoker. Once this burning of the gas, or vapors, 40 is initiated, the combustion supplies the necessary temperature of further ignitions and such adjacent combustion further raises the temperature of the mass sufficiently to cause its assuming the peculiar weight and structure mentioned above. In 45 a fuel of the described characteristics, there appears no distinct bubble structure, but rather it appears uniformly granular to the naked eye. Upon examination under a magnifying glass, this fuel appears to have drusy cavities of very uniform 50 form size.

The present invention contemplates not only automatic stoking of the furnace, but also semi-automatic ash disposal. As the grate 9 rotates slowly, the ashes evolved by the combustion of the fuel in the furnace are carried into contact with the hook end 37 of the ash ejector 35. Some of the ashes will be automatically directed to and through the aperture 34, and the remainder may be carried to said aperture by manual actuation of said ejector. When the ashes fall through the aperture 34 into the conduit 33, they are picked up by the thread 42 on the tube 28 and carried to the upper end of the tube 33, where they are allowed to fall through the aperture 43 into the 60 ash container 31. The gaps in the thread 42 make that thread inefficient and provide for the retention in the tube 33 of rings of ashes which seal said tube to prevent the flow of air through the aperture 43, tube 33 and aperture 34 into the combustion chamber.

70 It will be obvious that numerous variations may be added to the described construction without departing from the spirit of the present invention. For instance, the fuel for the furnace may be supplied in paper boxes of a size adapted to fit

within the container 23, thus doing away with the nuisance of dust and dirt which will be thrown into the air if the container 23 is filled by a shovel or the like. Again, the elements 19, 23 and 31 may be dispensed with, and the conduit 33 and tube 28 may be extended to the point of storage of a very large supply of coal and to a point where a large amount of ashes may be deposited. By such means, it will be possible to operate a furnace for a whole season without any attention other than varying the time of operation of the motor 30 to provide for larger or smaller fires, since the stoker is of such capacity that it need not be run more than about ten minutes in every hour under normal conditions.

80 Other modes of applying the principle of my invention may be employed instead of the one explained, change being made as regards the mechanism herein disclosed, provided the means stated by any of the following claims or the 85 equivalent of such stated means be employed.

I therefore particularly point out and distinctly claim as my invention:

1. The combination with a furnace of a stoker comprising a basin, a hopper provided with a 100 discharge mouth positioned adjacent said furnace, means for supplying solid fuel to said hopper, a rotatable, inclined tube extending from the discharge mouth of said hopper to said basin, means for rotating said tube to cause the fuel 105 in the hopper to gravitate therethrough toward said basin, and means for carrying such fuel from said basin to the combustion chamber of said furnace.

2. The combination with a furnace of a stoker 110 comprising a basin, a hopper provided with a discharge mouth positioned adjacent said furnace, means for supplying solid fuel to said hopper, a rotatable, inclined tube having its upper end located in the discharge mouth of the 115 hopper and its lower end located in an inlet conduit formed on said basin, means for rotating said tube, the upper end of said tube being beveled to agitate the fuel in the mouth of said hopper upon such rotation, and means for carrying the 120 fuel delivered through said tube from said basin to the combustion chamber of said furnace.

3. The combination with a furnace of a stoker comprising a basin, a hopper provided with a 125 discharge mouth positioned adjacent said furnace, means for supplying solid fuel to said hopper, a rotatable, inclined tube having its upper end located in the discharge mouth of the hopper and its lower end located in an inlet conduit formed on said basin, means for rotating said 130 tube to cause fuel from said hopper to gravitate through said tube and into said conduit, the lower end of said tube being beveled and adapted to push fuel through said conduit and into said basin upon such rotation, and means for carrying the fuel from said basin to the combustion 135 chamber of said furnace.

4. The combination with a furnace of a stoker comprising a basin, a hopper provided with a 140 discharge mouth positioned adjacent said furnace, a rotatable, inclined tube having its upper end beveled and located in the discharge mouth of the hopper and having its lower end beveled and located in an inlet conduit formed on said basin, means for rotating said tube, and means 145 for carrying fuel from said basin to the combustion chamber of said furnace.

5. The combination with a furnace of a stoker comprising a basin, a stator stationarily mounted in said basin and projecting upwardly therefrom 150

- into said furnace, a rotatable cylinder surrounding said stator and communicating with said basin, a thread on said stator contacting the inner cylindrical surface of said cylinder, a grate connected to said cylinder and rotatable therewith, gear teeth formed on said grate, a hopper provided with a discharge mouth and located adjacent said furnace, means for supplying solid fuel to said hopper, a rotatable, inclined tube 10 extending from the discharge mouth of said hopper to said basin, a motor mounted adjacent said tube, a worm and gear connection between said motor and said tube, and a gear on said tube in mesh with the teeth of said grate.
15. 6. The combination with a furnace of an automatic stoker and ash remover comprising a rotatable grate, an inclined conduit mounted adjacent said grate, a rotatable tube in said conduit, a hopper for supplying fuel to said tube, said tube communicating with said furnace, an aperture in said conduit adapted to receive ashes falling from said rotatable grate, a thread externally formed on said tube and contacting the inner wall of said conduit, and means for rotating said tube.
7. The combination with a furnace of a stoker and ash remover comprising a basin, a stator stationarily mounted in said basin and projecting upwardly therefrom into said furnace, a tubular rotor and a rotatable hearth surrounding said stator, a thread on said stator contacting the inner cylindrical surface of said tubular rotor, a grate connected to said tubular rotor and rotatable therewith, gear teeth formed on said grate, a shield concentric with said tubular rotor and spaced therefrom, said shield being mounted on said grate, a cowl projecting from the upper open end of said tubular rotor and overhanging the upper end of said shield, a hopper for solid fuel positioned adjacent said furnace, an inclined conduit extending between said hopper and said basin, a rotatable tube in said conduit having its upper end beveled and located in the discharge mouth of the hopper and having its lower beveled end located in an inlet conduit formed on said basin, an aperture in said inclined conduit adapted to receive ashes falling from said rotatable grate, a thread externally formed on said tube and contacting the inner wall of said conduit, a motor mounted adjacent said tube, a worm on the spindle of said motor, a worm gear on said tube and engaging said worm, a gear on said tube meshing with the teeth on said grate, an aperture formed in said tubular rotor within said basin, and a fin carried by said tubular rotor adjacent said aperture.
8. The combination with a furnace of a stoker comprising a basin, a stator stationarily mounted in said basin and projecting upwardly therefrom into the combustion chamber of said furnace; a hearth in said furnace disposed above said basin, a tubular rotor surrounding said stator and in communication with said basin,
5. tubular shield surrounding said rotor and spaced therefrom, means for feeding fuel to said basin, and means including said stator and rotor for conveying said fuel from said basin to said combustion chamber.
9. The combination with a furnace of a stoker comprising a basin, a stator stationarily mounted in said basin and projecting upwardly therefrom into said furnace, a hearth in said furnace disposed around said stator adjacent the bottom thereof, a tubular rotor surrounding said stator and in communication with said basin, a tubular shield surrounding said rotor and defining an insulating space therebetween, means for feeding fuel to said basin and means including said stator and rotor for conveying said fuel from said basin to the combustion chamber of said furnace.
10. The combination with a furnace of a stoker comprising a basin, a stator stationarily mounted in said basin and projecting upwardly into said furnace, the combustion chamber of said furnace surrounding said stator for the greater part of its length, a tubular rotor disposed around said stator and in communication with said basin, a tubular shield concentric with said rotor and separating the same from said combustion chamber, means for feeding fuel to said basin, and means including said stator and rotor for conveying said fuel from said basin into said combustion chamber.
11. The combination with a furnace of a stoker comprising a basin, a stator stationarily mounted in said basin and projecting upwardly into the combustion chamber of said furnace, a hearth in said furnace disposed above said basin, a tubular rotor surrounding said stator, the stator being provided with a screw thread contacting the adjacent surface of the rotor, a tubular shield surrounding said rotor, means for feeding fuel into said basin, an aperture in the wall of said rotor within said basin for admitting fuel to the space between said stator and said rotor, and means for rotating said rotor to force fuel upwardly through said space to the top of said rotor and into said combustion chamber.
12. The combination with a furnace of a stoker comprising a basin, a stator stationarily mounted in said basin and projecting upwardly into the combustion chamber of said furnace, a hearth in said furnace disposed around said stator adjacent the bottom thereof, a tubular rotor surrounding said stator, a tubular shield surrounding said rotor, a screw thread on said stator contacting the inner surface of said rotor, means for feeding fuel into said basin, an aperture in the wall of said rotor within said basin, a fin carried by said rotor adjacent said aperture, and adapted to direct said fuel through said aperture from said basin to the lower part of said screw thread, and means for rotating said rotor.

FRANK C. GREENE.
